UNITED STATES PATENT OFFICE.

EDWARD D. CALLEN, OF GREENVILLE, MISSISSIPPI

EXCAVATOR.

1,248,262.

Specification of Letters Patent. Patented Nov. 27, 1917.

Application filed August 18, 1917. Serial No. 185,982.

To all whom it may concern:

Be it known that I, EDWARD D. CALLEN, a citizen of the United States, residing at Greenville, in the county of Washington and State of Mississippi, have invented a new and useful Excavator, of which the following is a specification.

This invention relates to excavators of the scraper type, one of its objects being to provide a machine of this character which can be operated by means of an ordinary stationary engine and by a single person, means being provided whereby, when the machine is moved in one direction over the ground to be excavated, the parts will become automatically set so that, upon the return movement of the machine, the shovel thereof will dig into and remove a portion of the soil and convey it to the point of discharge, means being employed for automatically ejecting the dirt from the shovel after the same has been conveyed to a desired point.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings the preferred form of the invention has been shown.

In said drawings:

Figure 1 is a plan view of the machine.

Fig. 2 is a side elevation thereof.

Fig. 3 is a section on line 3—3 Fig. 2.

Fig. 4 is a longitudinal section through the machine.

Fig. 5 is a section on line 5—5 Fig. 2.

Fig. 6 is a diagrammatical view of the complete apparatus.

Referring to the figures by characters of reference 1 designates the main frame of the machine, the same being supported, at one end, by a single wheel 2 while its other end is supported by wheels 3 mounted for rotation upon the end portions of an angular axle 4. This axle is slidably mounted within slots 5 formed in bearing plates 6 attached to the sides of the frame 1, said slots being

inclined upwardly toward the front end of the machine, as shown in Fig. 2. A cross bar 7 is secured upon the frame 1 in advance of the axle 4 and is provided, upon the middle portion thereof, with a bracket 8 carrying spaced sheaves 9.

Forwardly converging strips 10 are secured to the axle 4 at points between the sides of the frame 1 and these strips merge into a guide tongue 11 which is slidably mounted within an opening 12 formed within a guide plate 13 secured to the front end of the frame 1 at the center thereof. This tongue thus operates to prevent the axle from shifting laterally relative to the frame 1, it being understood that the end portions of the axle are provided with shoulders 14 adapted to slide along the inner faces of the slotted plates 6, as shown particularly in Fig. 5.

Hangers 15 are connected to the sides of frame 1 back of the axle 4 and the sides of a shovel 16 are pivotally connected to the hangers, said shovel extending forwardly under the axle and being provided, adjacent its front end, with links 17 pivotally connected to the sides of the shovel. These sides are also connected to the main frame 1 by means of chains 18 adapted to limit the downward movement of the shovel relative to the main frame.

The links 17 are pivotally connected, at 85 their upper ends, to bars 19 which are arranged between the sides of the frame and are pivotally mounted, at their rear ends, upon a shaft 20 adapted to slide within slots 21 formed within supporting plates 22. 90 These plates are attached to the side of the main frame 1. Longitudinal slots 23 are formed within the bars 19 and each of these slots receives one end portion of a bar 24 adapted to slide therein. An arm 25 extends downwardly and forwardly from the middle portion of this bar and is pivotally connected, as at 26, to the middle portion of an ejecting plate 27 which is slidably mounted on the bottom of the shovel 16.

Sheaves 28 are connected to the rear end portions of the strips 10 and cables 29 extend partly around these sheaves and are fastened, at one end, to the bar 24, while their other ends extend through openings 30 105 in the rear end portion of the frame 1. The

cables 29 are secured together at a point back of the main frame 1 and are also fastened to a return or backing cable 31. This return cable is mounted on a sheave 32 supported by any suitable structure at a point beyond one limit of the path of movement of the machine and from sheave 32 the said return cable 31 extends longitudinally above the frame 1 and through bracket 8 and over one of the sheaves 9. Said return cable then extends throughout the path of movement of the machine and is attached to a drum X adapted to be rotated by a suitable engine Y.

Sheaves 33 are secured to the sides of frame 1 adjacent the bar 7 and additional sheaves 34 are secured to the sides of the shovel 16 near the front end of the shovel. Cables 35 are fastened at one end to the axle 4 close to the wheels 2 and these cables extend over the sheaves 33 and thence downwardly under the sheaves 34. The cables 35 extend forwardly and are secured together and to a loading cable 36 extending to another winding drum Z of the engine. If desired this cable 36 can be a continuation of the cable 31.

Anti-friction rollers 37 are carried by the upper end portions of the links 17 and are adapted, under certain conditions, to travel under the cross bar 7.

A sheave 38 is mounted within a bracket 39 connected to the rear end portion of the frame 1 and a cable 40 is mounted on this sheave 38 and is attached, at one end, to the cross bar 24. This cable extends forwardly from sheave 38 through the bracket 8 and over one of the sheaves 9 to a point where it can be conveniently reached for the purpose hereinafter set forth.

For the purpose of guiding the apparatus, the wheel 2 may be provided with a stem 41 having a worm gear 42. This gear is engaged by a worm 43 at one end of a steering rod 44. A hand wheel 45 is provided for actuating this mechanism so that a person traveling with the apparatus can hold it readily in its course.

Under normal conditions the bar 24 is seated within the rear ends of the slots 23, the shaft 20 is seated in the rear ends of the slots 21, plate 27 is located within the rear end of the shovel 16, and the anti-friction rollers 37 are located back of the cross bar 7. By winding cable 31 and successively holding and paying out cable 36, the cables 29 will be caused to pull bar 24 forwardly within the slots 23, thus sliding the scraper plate 27 forwardly within the shovel 16 resting on the ground and ejecting any dirt which may have been accumulated within the shovel. During the completion of this forward movement of bar 24, the same pushes against the front end walls of the

slots 23 and thus causes the bars 19 to move forwardly to bring rollers 37 under the cross bar 7. Upon the completion of the forward movement of bar 24, further pulling of the cables 29 will cause the sheaves 28 to pull axle 4 rearwardly against the upper inclined walls of the slots 5, thus causing the main frame 1 to be elevated so as to lift the shovel off of the ground. Further winding of the cable 31 will move the machine bodily toward the sheave 32 located at one end of the path of movement of the machine. When the machine has traveled a desired distance toward the sheave 32, the winding of cable 31 is discontinued and cable 36 is then taken up while cable 31 is permitted to become slack. When cables 36 and 35 become taut, they first pull the axle 4 forwardly within the slots 5, thus permitting the main frame 1 to gravitate downwardly so as to bring the front edge of the shovel into contact with the ground. Continued pulling of the cables 35 and 36 will move the machine forwardly away from the sheave 32 and toward the other limit of the path of movement of the machine. As the machine is thus drawn forwardly, the shovel digs into the soil and as the soil accumulates within the shovel, it pushes the ejecting plate 27 backwardly. The shovel can not ride over the ground during this forward movement because the links 17 are prevented from moving upwardly by the cross bar 7 under which the rollers 37 are arranged. As the shovel becomes filled during the forward movement of the machine, bar 24 moves against the rear end walls of the slots 23 and thus shifts the bars 19 longitudinally so as to move the rollers 37 from under the cross bar 7. Shovel 10 is thus unlocked. After the dirt has been conveyed to the point of discharge, the winding of cable 36 is stopped and held, said cable is permitted to become slack. Cable 31 is then wound so as to start the machine in the reverse direction. During the first portion of the winding operation, cable 31 will cause the plate 27 to move forwardly within the shovel 16 which is held back by cable 36 and thus eject the contents of the shovel after which the parts will become reset and by releasing drum Z and cable 36 can be moved toward the sheave 32 as hereinbefore described.

It will be apparent that by using a machine such as has been described, one person, operating the driving engine, can control the entire operation of the excavator simply by starting and stopping the winding drum so as to move the machine in the proper direction.

By providing the cable 40, the operator can pull the bar 24 rearwardly should the parts become caught from any cause and

not operate as smoothly as desired. This manual actuation of the parts will not often be necessary and usually only occurs when some of the parts become clogged.

It is to be understood that if desired the wheels on the apparatus can be replaced with runners to be drawn over the ground.

What is claimed is:-

1. An excavator including a shovel, actuating means for moving the same backwardly, and means operated by said actuating means for successively ejecting the contents of the shovel, elevating the shovel, and locking the shovel prior to the backward movement thereof.

2. An excavator including a shovel, actuating means for moving the same backwardly, and means operated by said actuating means for successively elevating and locking the shovel prior to the backward movement thereof.

3. An excavator including a shovel, a supporting structure therefor, actuating means for moving said structure and shovel backwardly, and means operated by said actuating means for successively elevating the structure and locking the shovel against upward movement relative to the structure, prior to the backward movement of the shovel and structure.

4. An excavator including a shovel, a supporting structure therefor, actuating means for moving the structure and shovel backwardly, and means operated by said actuating means prior to the backward movement of the structure and shovel, for successively ejecting the contents of the shovel, elevating the structure, and locking the shovel against upward movement relative to the structure.

5. An excavator including a shovel, means for locking the same in lowered position, means operated by the pressure of material accumulated within the shovel for unlocking the shovel, means for pulling the shovel forwardly, said means operating to elevate the shovel when unlocked, means for moving the shovel rearwardly, and means for automatically ejecting the contents of the shovel prior to the rearward movement thereof.

6. Excavating apparatus including a motor, a shovel carrying structure, means operated by the motor, when driven in one direction, for successively ejecting the contents of the shovel, locking the shovel, and moving said shovel rearwardly, and means operated by the motor when driven in the opposite direction, for successively moving the shovel forwardly to accumulate material therein and elevate the shovel, said ejecting means being operable by the accumulated material on the shovel to unlock said shovel to permit the elevation thereof.

7. An excavator including a shovel, operating means for moving the shovel forwardly, operating means for moving the shovel rearwardly, an element movably mounted on the shovel, means operated by the backwardly actuating means for shifting said element to eject the contents of the shovel and to lock said shovel, and means operated by the forwardly actuating means for elevating the shovel when unlocked, said element on the shovel being operable by material accumulated within the shovel, to unlock the shovel.

8. An excavator including a wheel supported structure, a shovel movably mounted therein, a backing cable, means operated thereby for successively ejecting the contents of the shovel, elevating the structure, and locking the shovel against upward movement relative to the structure, prior to the backing of the excavator, a loading cable, and means operated thereby for successively pulling the excavator forwardly and elevating the shovel when unlocked, said ejecting means being operable by material accumulated on the shovel to unlock the shovel.

9. An excavator including a wheel supported structure, a shovel pivotally connected thereto and suspended therefrom, longitudinally slotted bars pivotally and slidably mounted within the structure, link connections between the bars and the shovel, an ejecting plate slidably mounted upon the shovel, a slideable connection between said plate and the slotted bars, a backing cable, guides therefor, said cable being connected to the slideable connection and constituting means for shifting said connection relative to the bars and for shifting the bars, and means carried by the wheel supported structure and coöperating with said links for locking the links and the shovel against upward swinging movement relative to the wheel supported structure.

10. An excavator including a wheel supported structure, a shovel pivotally connected thereto, a cross bar upon the structure, bars pivotally and slidably connected to the structure, link connections between said bars and the shovel, said connections being movable under the cross bar to lock the shovel against upward movement, a loading cable, said cable being connected to the structure, guides therefor mounted upon the shovel, said cable exerting a constant lifting action upon the guides during the forward movement of the structure, and means upon the shovel and operable by material accumulating on the shovel, for shifting the links from under the cross bar to unlock the shovel.

11. An excavator including a wheel supported axle, a frame extending thereacross,

bearing plates slidably engaged by the axle, said plates having inclined axle receiving slots, a shovel carried by the structure, a backing cable, a loading cable, and means 5 operated by the respective cables for shifting the axle in opposite directions respectively within the slots to raise and lower the structure relative to the axle.

In testimony that I claim the foregoing as my own, I have hereto affixed my signature in the presence of two witnesses.
